Primary Examiner — Katrina A Betton(74) *Attorney, Agent, or Firm* — J.T. Hollin Attorney at Law, P.C.(57) **CLAIM**

I claim the ornamental design for a vehicle trailer body, as shown and described.

DESCRIPTION

FIG. 1 is a perspective view of the design of the front and left side of the vehicle trailer body.

FIG. 2 is a direct elevation view of the front of the vehicle trailer body.

FIG. 3 presents a direct elevation view of the rear of the vehicle trailer body; and,

FIG. 4 is an elevation view of the right side the vehicle trailer body.

In the drawings presented, it will be understood that the broken lines are for illustration only, and do not form a part of the claimed design.
